(57) **CLAIM**

The ornamental design for the fishing float, as shown and described.

DESCRIPTION

FIG. 1 is a top perspective view of the fishing float showing my new design;

FIG. 2 is a bottom perspective view thereof;

FIG. 3 is a top plan view thereof;

FIG. 4 is a front view thereof, the rear and side views being identical;

FIG. 5 is a bottom plan view thereof;

FIG. 6 is a top view, with an insert in the passage way through the fishing float;

FIG. 7 is a front view, with one or more inserts in the passage way;

FIG. 8 is a bottom view with an insert in the passage way, wherein the bottom includes a circular marking around the passage way through the fishing float;

FIG. 9 is a perspective view, with an insert in the passage way;

FIG. 10 is a bottom perspective view with an insert in the passage way, wherein the bottom includes a circular marking around the passage way through the fishing float; and,

FIG. 11 is a top perspective view, wherein the top surface includes a circular marking around the passage way through the fishing float.

The broken lines in the drawings are for illustrative purposes only and form no part of the claimed design.
